No. 858,334.

PATENTED JUNE 25, 1907.

W. EICHELBERGER.
FUEL ECONOMIZER SOOT CLEANER.
APPLICATION FILED APR. 22, 1907.

UNITED STATES PATENT OFFICE.

WILLIAM EICHELBERGER, OF DUBOIS, PENNSYLVANIA, ASSIGNOR TO THE
VULCAN SOOT CLEANER COMPANY OF PITTSBURG PA., OF DUBOIS,
PENNSYLVANIA, A CORPORATION OF NEW JERSEY.

FUEL-ECONOMIZER SOOT-CLEANER.

No. 858,334.

Specification of Letters Patent.

Patented June 25, 1907.

Application filed April 22, 1907. Serial No. 369,633.

To all whom it may concern:

Be it known that I, WILLIAM EICHELBERGER, a citizen of the United States of America, residing at Dubois, in the county of Clearfield and State of Pennsylvania, have invented certain new and useful Improvements in Fuel-Economizer Soot-Cleaners, of which the following is a specification, reference being had therein to the accompanying drawing.

10 Fuel economizers, for the purpose of heating water preliminary to its passage into the boiler, by the use of the waste gases and other products of combustion, are generally located in the path of travel of such products leading from the boiler or boilers to the chimney or stack, and comprise a chamber having a plurality of spaced vertically-extending tubes mounted in series, the upper and lower ends of the tubes being connected by horizontally-extending tubes or connections extending crosswise of the chamber, thereby presenting a series of vertically-extending tubes across the path of travel of the gases and other products of combustion. The 15 lines of tubes are arranged in series and with suitable connections to provide a circulation of water therethrough and the chamber is preferably an enlarged portion of the passage leading from the boiler to the chimney, each 20 line of tubes being of sufficient length to extend practically across the chamber.

As the tubes are located within the path of travel of the products of combustion, the outer surfaces of the tubes quickly collect the 25 soot particles carried by such products, thereby preventing the maximum application of the heat to the tubes. To prevent this suitable tube-cleaners are employed, said cleaners being adapted to travel vertically over the surfaces of the tubes, these movements removing the soot particles and scale which may collect on the tubes, in a manner similar to a scraper, the particles thus removed dropping downward into a soot- 30 collecting chamber located below the plane of the lower horizontally-extending pipes.

As the lower pipes or tubes are on a plane approximate that of the bottom of the smoke-flue or passage for the products leading from 35 the boiler flues, and present obstructions to the passage of such products, the latter passing above said horizontally-extending pipes or tubes in passing to the chimney, the soot-

chamber is located out of the path of travel of such products and thereby provides a collecting chamber for the soot and other particles. 55

In order to procure a maximum amount of service from the waste products without, however, providing a structure of such length as to affect the natural draft of the boiler or boilers, as well as to permit of the use of a cleaning device or devices which are not unwieldy in operation and which will operate on a maximum number of tubes simultaneously, 60 the tubes are arranged relatively close together both lengthwise and across the chamber. In operating devices of this character, however, it has been found that while the vertically-extending tubes are kept substantially clear of soot particles by the moving cleaners, the necessity of arranging the tubes close together, and the inability of the cleaners to move downward into contact with the horizontally-extending tubes permits the 65 particles to gather on the horizontally-extending tubes and the couplings of the said tubes and the vertically-extending tubes, with a gradually-increasing tendency to close the space between the horizontal pipes 70 and thereby prevent the dropping of the particles into the soot-chamber as well as to tend to decrease the heating power of said horizontal tubes. To overcome this difficulty 75 the present invention is provided.

As indicated, the invention relates to fuel-economizers and has for one of its objects the provision of means for clearing the lower portions of the circulating systems thereof of soot or other particles. This object is accomplished by projecting a series of steam jets from the soot-chamber in a direction angular with respect to the path of travel of the products of combustion, said jets passing through the spaces between the tubes and 80 dislodging the particles from said tubes, said particles passing into the current forming the natural draft and passing with it into the 85 chimney.

The further object of the invention is to 90 provide means for projecting a plurality of steam jets in a direction which will tend to raise the soot contained within the soot-chamber, the raising of the soot particles carrying them into the path of travel of the 95 products of combustion.

To these and other ends the nature of which will be readily understood as the invention is hereinafter disclosed, said invention consists in the improved construction 5 and combination of parts hereinafter fully described, illustrated in the accompanying drawings, and particularly pointed out in the appended claims.

In the drawings, in which similar reference 10 characters indicate similar parts in each of the views,—Figure 1 is a vertical longitudinal sectional view through the lower portion of a fuel-economizing system, showing the arrangement of tubes therein, the moving 15 tube-cleaners, the soot-chamber, and the invention herein disclosed located therein. Fig. 2 is a sectional view of the same taken on line 2—2 of Fig. 1. Fig. 3 is a sectional view taken on line 3—3 of Fig. 1. Fig. 4 is a 20 detail sectional view showing the location and arrangement of the jet-producing perforations. Fig. 5 is a detail view of one of the pipes hereinafter particularly referred to.

In describing the invention, I will first describe in general terms the structure of so 25 much of a fuel-economizer as is shown in the drawings, in which 10 indicates the smoke-flue or passage for the products of combustion leading from the boiler-flues; 11, designates the chamber for the circulating tubes, and 12 the soot-chamber. The outlet from the chamber 11 is not shown, but will be understood to be at the end of the chamber 11 opposite that of the flue 10.

13 designates a series of vertically-extending tubes connected at their lower ends to the horizontal tubes 14 extending cross-wise of the chamber 11, and 15 designates the tube cleaners movable vertically over the 40 surfaces of the tubes 15 by suitable means (not shown), the structure selected for illustration being that known as the "Green Fuel Economizer." The particular operation of these parts have been heretofore described 45 and it is not believed to be necessary to again refer to it excepting as is necessary in the following description of this invention in connection therewith.

20 designates a steam-pipe connected to a 50 suitable source of steam-supply, said pipe being located outside of and in a direction longitudinal of the soot-chamber. A valve 21 controls the passage of steam thereto. At suitable intervals along said pipe 20 are located branch pipes 22, each having a valve 23, and each having at its opposite end a coupling to which are secured two pipes 24 which extend through the walls of and into the soot-chamber, said pipes extending cross- 55 wise of said chamber preferably to a point approximate the opposing wall of the chamber. Said pipes 24 are provided with a series of perforations 25, said perforations being arranged in staggered form, as shown in Fig. 4. 60 The upper row of perforations are adapted to

direct the jets of steam issuing therefrom upwardly in a relatively inclined direction, as indicated by the arrows 26 in Fig. 1, while the other row of perforations is adapted to direct the steam jets in a horizontal direction, as shown in said figure. The pipes 24 may, if desired, be provided with nozzles in lieu of the apertures 25. The jets of steam from the upper row of perforations are projected toward the pipes or tubes 14, the direction 75 of projection is not truly vertical (which would tend to pass them into the path of travel of the products of combustion at a right angle) but is in a direction angular with respect to such path of travel, the angle inclining toward the direction of the flow of the products passing through the chamber 11 so that the soot particles dislodged by the jets will be passed into the current and if not of sufficient weight to drop back and into the 80 soot-chamber, will be carried out through the chimney. In addition, the direction in which the steam jets are projected will tend to increase the draft through the chamber 11. The jets of steam from the lower row of 85 perforations are mainly intended to be used for the cleaning of the soot-chamber itself, said perforations directing the steam jets in a direction parallel with and adjacent the bottom of the soot-chamber, thereby raising the soot 90 and tending to carry it into the path of the natural draft, or into the path of the upper row of steam jets by which it would be moved into the natural draft. That portion 95 of the soot which would be carried directly 100 rearward and which would lodge against the wall of the soot-chamber, would be raised by the steam jets issuing from the perforations 25^a, located at the top of the last pipe, 105 designated at 24^a, said steam-jets being directed substantially vertically, said structure raising the soot at that end of the chamber and carrying it into the path of travel of the products of combustion at a point where its 110 further movement must be in the direction 110 of the chimney.

While I have shown two pipes 24 connected to each branch-pipe 23, it is to be understood that the number of such pipes connected to each branch may be more or less 115 than this number, as desired. As each branch-pipe is controllable as well as is the entrance of steam into the pipe 20, it will be understood that the projection of the steam jets is under the entire control of the operator. 120

The operation of the device is believed to 125 be obvious, and it will be understood that the steam is not projected continuously but only when necessary, and that to obtain the best results in cleaning the soot chamber, the pipes 24 are successively opened so as to begin the operation at the front, the continued addition of steam jets from successive pipes increasing the effect. 130

Having now described my invention, but without pointing out more than one particular structure for carrying the same into effect, reserving to myself the right to use any and all modifications thereof as may fall within the spirit and scope of the invention, what I claim as new is:—

1. A fuel-economizer system including an inclosed water-circulating structure located within the path of travel of the products of combustion, movable means for clearing the exposed surfaces of the main portion of said structure, and auxiliary means for clearing the surfaces of the lower portion of said structure.

2. A fuel-economizer system including an inclosed water-circulating structure located within the path of travel of the products of combustion, movable means for clearing the exposed surfaces of the main portion of said structure, and auxiliary means for clearing the surfaces of the lower portion of said structure, said means assisting the natural draft passing through said structure.

3. A fuel-economizer system including an inclosed water-circulating structure located within the path of travel of the products of combustion, movable means for clearing the exposed surfaces of the main portion of said structure, and auxiliary means for clearing the surfaces of the lower portion of said structure, said means being located out of the normal path of travel of the products.

4. A fuel-economizer system including an inclosed water-circulating structure located within the path of travel of the products of combustion, movable means for clearing the exposed surfaces of the main portion of said structure, and auxiliary means for clearing the surfaces of the lower portion of said structure, said means being located out of the normal path of travel of the products and operating to assist the natural draft passing through said structure.

5. A fuel-economizer system including an inclosed water-circulating structure located within the path of travel of the products of combustion, movable means for clearing the exposed surfaces of the main portion of said structure, and auxiliary means for clearing the surfaces of the lower portion of said structure, said means being located below the bottom of said structure.

6. The combination with a fuel-economizer system having an inclosed water-circulating structure located in the path of travel of the products of combustion, and also having a soot-chamber located below said path of travel, of means, located in said soot-chamber for projecting steam toward said structure and said path of travel.

7. The combination with a fuel-economizer system having an inclosed water-circulating structure located in the path of

travel of the products of combustion, and also having a soot-chamber located below said path of travel, of means located in said soot-chamber for projecting a plurality of steam jets.

8. The combination with a fuel-economizer system having an inclosed water-circulating structure located in the path of travel of the products of combustion, and also having a soot-chamber located below said path of travel of means located in said soot-chamber for projecting a plurality of steam jets in a direction angular with respect to said path of travel.

9. The combination with a fuel-economizer system having an inclosed water-circulating structure located in the path of travel of the products of combustion, and also having a soot-chamber located below said path of travel, of means located in said soot-chamber for projecting a plurality of steam jets in a direction angular with respect to said path of travel, the angle inclining toward the direction of flow of the products passing through said structure.

10. The combination with an inclosed water-circulating structure located in the path of travel of the products of combustion, of means located without said path for controllably projecting steam into contact with said structure to clear it from collected soot particles.

11. The combination with a fuel economizer system having a water-circulating structure located in the path of travel of the products of combustion and having a soot-chamber located therebelow, of means for carrying the soot contained within said chamber into the path of travel of the products of combustion.

12. The combination with a fuel economizer system having a water-circulating structure located in the path of travel of the products of combustion and having a soot-chamber located therebelow, of means located within the soot-chamber for carrying the soot contained within said chamber into the path of travel of the products of combustion.

13. The combination with a fuel economizer system having a water-circulating structure located in the path of travel of the products of combustion and having a soot-chamber located therebelow, of means located at the bottom of the soot-chamber for carrying the soot contained within said chamber into the path of travel of the products of combustion.

14. The combination with a fuel economizer system having a water-circulating structure located in the path of travel of the products of combustion and having a soot-chamber located therebelow, of means for projecting a plurality of steam jets in a direc-

tion to carry the soot contained within the soot-chamber into the path of travel of the products of combustion.

15. The combination with a fuel economizer system having a water-circulating structure located in the path of travel of the products of combustion and having a soot-chamber located therebelow, of means for projecting one series of steam jets in a direction angular with respect to the plane of the bottom of the soot-chamber and projecting another series of jets in a direction parallel with said bottom to carry the soot contained within the soot-chamber into the path of travel of the products of combustion.

16. The combination with a fuel economizer system having a water-circulating structure located in the path of travel of the products of combustion and having a soot-chamber located therebelow, of means for projecting one series of steam jets in a direction angular with respect to the plane of the bottom of the soot chamber and projecting another series of jets in a direction parallel with said bottom, means for forming a plurality of vertical steam jets adjacent the rear wall of the soot-chamber, being provided, the combined action of said steam jets being to

carry the soot contained within said chamber into the path of travel of the products of combustion. 30

17. The combination with a fuel economizer system having a water-circulating structure located in the path of travel of the products of combustion and having a soot-chamber located therebelow, of means for cleaning the surfaces of the lower portion of said water-circulating structure and the soot-chamber, the soot being carried into the path of travel of the products of combustion. 35

18. The combination with a fuel economizer system having a water-circulating structure located in the path of travel of the products of combustion and having a soot-chamber located therebelow, of means located within the soot-chamber for cleaning the surfaces of the lower portion of said water-circulating structure and the soot-chamber, the soot being carried into the path of travel of the products of combustion. 40

In testimony whereof I affix my signature in the presence of two witnesses.

WILLIAM EICHELBERGER.
